NONLIFTING TOWED TARGET GLIDER

Marion O. McKinney, Jr., and John P. Campbell,
Hampton, Va.

Application March 28, 1951, Serial No. 218,058

2 Claims. (Cl. 273—105.3)

(Granted under Title 35, U. S. Code (1952),
sec. 266)

1

This invention relates to airplane-shaped tow targets for use in simulation of air combat conditions.

Tow targets have been in common use in the form of towed gliders provided with conventional wings. These gliders, while satisfactory for lower speed uses have proven practically impossible for use at higher speeds due to general instability and lack of strength at these speeds. If the glider is of light construction the high speed loads produce distortion of the airframe which in turn causes excessive accelerations and trim changes. If of heavy construction to withstand air loads, trouble will be experienced in unstable lateral oscillations due to the high mass and moments of inertia.

The present invention meets the difficulties mentioned by removing the lift function from the wings, as it has been determined that there is no need for lift in a tow glider, and employing the wing only to make the target look like an airplane.

The objects of the invention therefore include provision of glider wings having nonlift attributes, serving primarily as a means of providing the target with the shape of an airplane, and having a configuration effective to reduce drag at high speeds.

A further object is to provide a glider suitable for tow target uses which is stable at airplane speeds in the neighborhood of 500 miles per hour, and which at the same time simulates airplane construction. Other objects will appear on consideration of the following description of a preferred embodiment of the invention taken in conjunction with the drawings in which

Fig. 1 is a perspective view of a glider with wings of conventional form pivoted axially ahead of the aerodynamic center;

Fig. 2 is a view of a modified non-lift wing form;

Fig. 3 is a view of the glider wing of Fig. 2 with a trailing flap;

Fig. 4 is a view of the glider wings of Fig. 3 with a swept back construction.

In Fig. 1 the tow target form is that of a conventional glider 10 bearing the usual fuselage 11 and tail fins including vertical fin 12 and stabilizer 13.

The wings 15 include right and left sections 16 and 17. Each of these sections is pivotally mounted on a rod support 18 extending laterally from the fuselage and in line with each other and is free to pivot independently or together about the spanwise axis of the wing section. The pivot rod is placed ahead of the aerodynamic center

5 of the wing to insure a strong tendency of wing alignment with the wind; also the wing is mass balanced to avoid flutter. Thus the lift function of the wings is removed, dependence for stability being placed primarily on the towline and glider tails with such stability factors as the modified wings afford.

10 By the described modification of the wing structure glider speeds in the neighborhood of 500 miles per hour become feasible without substantial changes in the overall construction form and weight as used in the conventional glider. At these high speeds there is satisfactory stability with marked reduction in sensitivity to trim changes and other modifying conditions.

15 It is pointed out that the wings are freely pivoted each entirely independently of the other, so that each wing automatically adjusts itself to the wind incidence, or the wings may be connected together for simultaneous operation. Also, as demonstrated by tests, the towline provides adequate bank stabilizations where the glider has zero lift, since the glider tends to trail below the towing airplane. It is, of course, necessary that the towline be attached to the glider ahead of and above the glider center of gravity, a value of one-tenth span above, and one-half span ahead of, the center of gravity, with a five degree towline angle, giving satisfactory results.

20 In Fig. 2 a modified form of wing 20 is shown with the airfoil sections 21 and 22 circular in section: i. e. rods or cylinders. These airfoils are adequate for the tow function but are deficient in visibility for target purposes, a defect which 25 may be rectified by hinging a panel or flaps 30 and 31 to the trailing edge of the airfoil sections 21 and 22 respectively, as indicated in Fig. 3, so that the flaps trail freely in the wind. The critical Mach number of a circular airfoil section wing is relatively low. Accordingly, in order to avoid 30 undue drag at high speeds, it may be desirable to sweep back the wing as shown by wings 40 and 41 in Fig. 4.

35 In all wing forms as shown in Figs. 1, 2 and 3, the nose of the wing airfoil is symmetrically contoured so that the profiles on both sides of the nose tip are similar but reversed. It is pointed out, also, that in all modifications the pitching moment or, as otherwise stated, the lift is zero.

40 Other modifications of the invention may be apparent to those skilled in the art and hence no limitation is intended by the specific disclosure other than may be required by the scope of claims hereto appended.

45 The invention described herein may be manu-

factured and used by or for the Government of the United States of America for governmental purposes without the payment of any royalties thereon or therefor.

What is claimed is:

1. A tow-glider comprising a fuselage, guide fins including stabilizers at the tail end of said fuselage, aligned rod-like elements of uniform circular cross-section secured to and extending transversely from said fuselage, a pair of wing 10 simulating flaps each pivoted freely on said elements at a respective one of both sides of said fuselage on a line intermediate the nose and rear edges of the flap and displaced toward the flap nose from the aerodynamic flap center whereby 15 a zero lift characteristic is attained, the flaps having profiles symmetrically contoured on both sides of the fuselage.

2. A tow-glider comprising a fuselage, guide fins including stabilizers at the tail end of said 20 fuselage, aligned support elements secured to and extending transversely from said fuselage on opposite sides thereof, a pair of wing simulating

flaps each pivoted freely on one of said elements on a line intermediate the nose and rear edge of the flap and displaced toward the flap nose from the aerodynamic flap center whereby a zero lift 5 characteristic is attained, the flaps having profiles symmetrically contoured on both sides of the fuselage.
